UNITED STATES PATENT OFFICE.

HERMAN SCHUTTE, OF WILKINSBURG, PENNSYLVANIA, ASSIGNOR TO SCHUTTE ELECTRIC COMPANY, OF PITTSBURGH, PENNSYLVANIA, A CORPORATION OF PENNSYLVANIA.

TROLLEY-WIRE HOLDER.

1,296,860.

Specification of Letters Patent. Patented Mar. 11, 1919.

Application filed April 25, 1918. Serial No. 230,832.

To all whom it may concern:

Be it known that I, HERMAN SCHUTTE, a citizen of the United States, residing at Wilkinsburg, in the county of Allegheny and State of Pennsylvania, have invented a new and useful Improvement in Trolley-Wire Holders, of which improvement the following is a specification.

My invention relates to improvements in devices for holding trolley wires. The object of my invention is to produce a simple, cheap and effective device of this character which may be readily assembled and disassembled when desired, and which when in use is automatically locked.

I accomplish these objects by means of the device hereinafter more specifically described, reference being had to the accompanying drawings, forming part hereof, in which:

Figure 1 is a side elevation of my improved device for holding trolley wires.

Fig. 2 is an elevation of the inner side of the socket member.

Fig. 3 is a section on line 4—4 of Figs. 1—2.

Fig. 4 is a plan view of a modified form of the device, one-half of the lock socket being removed.

Fig. 5 is a side elevation with one-half of one of the side plates removed.

Fig. 6 is an interior elevation of the side plate of the device.

Fig. 7 is an end view of same.

Fig. 8 is an end view of the device when assembled.

Fig. 9 is a plan view of side piece shown in Fig. 6.

Fig. 10 is a side elevation of the lock key.

Fig. 11 is a plan view of same.

Fig. 12 is a transverse section of key.

Fig. 13 is an end elevation of the lock socket.

Referring to said drawings, (and particularly to Figs. 1 to 3 inclusive) 1, 2 are the sides of the device, each of which is provided with interlocking loop members, 3, 4, 5, the side, 1, having also integrally formed therewith the socket, 6, by means of

50 which the device is attached to any suitable support. 7 is a key which is inserted from

the end of the device when the two side members are assembled, as shown in Fig. 1. The said key as shown is somewhat longer than the holder and has a groove or channel, 55 8, longitudinally thereof, in the upper edges of which are formed the staggered projections, 9, 10 and 11, which engage the lock loops 3, 4 and 5, of the side members, and when said key in normal use is moved in 60 a direction parallel with the trolley wire, the said toothed projections engage said loop members and maintain the device in locked position upon the wire, so that when said holder is not in use the toothed projections are readily disengaged from the loop members and the members of the holder 65 disassembled.

In Figs. 4 to 13 inclusive, I show a modified form of my device which is substantially identical with the device illustrated in Figs. 1 to 3, excepting that the socket, 12, is an independent member, 13, having a loop, 14, the side members, 15 and 16, being provided with loops, 17, 18 and 19, and 75 with semi-circular openings, 20 and 21, on the upper side midway their length, in which the socket, 12, is adapted to be seated, as shown in Figs. 1 and 2.

Having described my invention, what I 80 claim and desire to secure by Letters Patent, is:

1. A trolley wire holder comprising two side members having projecting, interlocking, loop members, a key having serrations 85 on its edges, the edges thereof being adapted to engage said loop members and lock the same firmly together, and means to attach said holder to a support.

2. A trolley wire holder comprising two side members having interlocking laterally projecting loop members, the lower edges of said side members having means for holding a trolley wire, and a key having serrations on its edges, the edges thereof being 95 adapted to engage the loop members and lock the said side members firmly together and upon said trolley wire when said key is moved in a direction with the trolley wire.

3. A trolley wire support comprising two side pieces having laterally projecting in-

terlocking loop members, one of said side pieces having a socket formed integral therewith, the lower edges of said side members having means for holding a trolley wire, in combination with a key having serrations along its edges, adapted to engage said loop members, and lock the same firmly together and upon the trolley wire.

Copies of this patent may be obtained for five cents each, by addressing the "Commissioner of Patents, Washington, D. C."

In testimony whereof, I have hereunto signed my name in the presence of two subscribing witnesses.

HERMAN SCHUTTE.

In the presence of—

ALEX. S. MABON,
HELEN E. WEIS.
